TROUSER AND SKIRT HANGER

Charles J. Stager, Troy, Ohio

Application March 7, 1950, Serial No. 148,077

3 Claims. (Cl. 223—96)

1

This invention relates to garment hangers, and more particularly to a device for holding garments such as trousers or skirts and being of the type provided with opposing clamping jaws and having spring means for holding the jaws in clamping position.

A main object of the invention is to provide a novel and improved garment hanger for holding garments such as trousers, skirts, and the like, said hanger being simple in construction, involving only a few parts, and being very easy to manipulate for placing a garment in the hanger and for releasing the garment therefrom.

A further object of the invention is to provide an improved garment hanger for supporting trousers, skirts and the like, said hanger being inexpensive to manufacture, being sturdy in construction, being very compact in size, and being provided with means for locking the jaw portions of the hanger in gripping positions when the hook portion of the hanger is in its upstanding position.

Further objects and advantages of the invention will become apparent from the following description and claims, and from the accompanying drawings, wherein:

Figure 1 is a front elevational view of an improved garment hanger constructed in accordance with the present invention, said view showing a portion of a hanger rack on which the hook portion of the garment support is suspended, the rack being shown in cross section.

Figure 2 is a top plan view of the improved garment hanger illustrated in Figure 1.

Figure 3 is a cross sectional view taken on line 3—3 of Figure 1.

Figure 4 is a view similar to Figure 3, but showing the hook element of the hanger in a downwardly swung position, whereby the gripping jaws of the hanger may be released.

Figure 5 is a perspective detail view of the hook element of the garment hanger of Figures 1 to 4.

Referring to the drawings, 11 and 12 respectively designate wire rod members bent and fastened to define substantially rectangular frames, involving the lower longitudinal arm 13 of the rectangular frame 11 and the lower longitudinal arm 14 of the rectangular frame 12, said lower longitudinal arms being arranged parallel to and adjacent to each other, as shown in Figures 3 and 4. The upper longitudinal arm of the frame 11 has laterally offset portions 15 terminating in coils 16 coiled around the upper longitudinal arm of the frame 12 so as to define longitudinally aligned hinges, the portion 17 of the

upper arm of frame 11 between the coils being upwardly and laterally inwardly offset with respect to the axis of said hinges, as shown in Figures 1 and 3. The intermediate portion 18 of the upper arm of the rectangular frame 12 is downwardly and laterally outwardly offset with respect to the hinges. At its middle the intermediate portion 18 is formed with an upwardly deflected bend 19 and pivotally secured to said bend is the lower end of the hook member 20. The shank of the hook member is formed with a right angle portion 21 which is adapted to engage beneath an upwardly deflected bend 22 formed at the middle of the intermediate portion 17, in the manner shown in Figure 3, whereby when the hook member 20 is in an upstanding position, the right angle portion 21 locks the element 17 against rotation in either direction as long as the hook element is hooked over a hanger bar, such as shown at 23, and carries its load.

Encircling the end portions of the upper arm 17 of the rectangular frame 12 are respective coil springs 24, 24, the outer end of each coil spring being anchored at 25 against the end arms of the frame 12 and the inner ends of said springs being secured to the upstanding elements of the hinge coil 16, 16, as shown in Figure 1. The springs 24, 24 thereby act to bias the lower longitudinal arms 13, 14 toward each other and provide a gripping force between said lower arms. Said lower arms are laterally outwardly bent at their intermediate portions, as shown at 26, 27. The outwardly bent portions 26 and 27 therefore define spaced gripping portions on each of the arms 13, 14, said gripping portions being located at the ends of said arms. The respective gripping portions of the arms 13, 14 are provided with rubber cushioning sleeves 28 which serve as means for preventing creases from being pressed into garments held between the gripping arms 13, 14.

To insert a garment between the gripping arms 13, 14, the hook member 20 is first swung downwardly to the position shown in Figure 4, thereby releasing the upper portion 17 of the top arm of frame 11 for rotation. The user then grasps the elements 17 and 18 of the garment hanger and rotates the arm 17 clockwise with respect to the arm 18, as viewed in Figure 3, thereby separating the gripping arms 13, 14. The garment to be supported is then inserted between the gripping arms, and then the elements 17 and 18 are released, allowing the springs 24, 24 to bring the gripping arms toward each other and exert a gripping force on the garment. The hook member 20 is then rotated upwardly toward the posi-

tion of Figure 3, wherein the right angle bend 21 underlies the bend 22 and locks the element 17 against rotation with respect to the remainder of the hanger, whereby the gripping jaws 13, 14 may not be separated when the hook element 20 is in said vertically rotated position. It is therefore apparent, that once a garment has been secured in the hanger and has been hung, accidental disengagement of the garment from the hanger is substantially prevented and the garment will remain in a suspended position as long as the garment hanger is suspended from its supporting rack.

Although a specific embodiment of a garment supporting device has been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. In a garment hanger, two longitudinally elongated rectangular frames arranged in side by side relation, each frame comprising a first longitudinal arm, a second longitudinal arm laterally spaced from the first longitudinal arm, and end arms extending between longitudinally outward end portions of the longitudinal arms, the second longitudinal arms of the frames having laterally offset intermediate portions spaced from the longitudinally outward ends thereof and extending parallel to said first longitudinal arms of the frames, the offset intermediate portion of one frame being offset toward the first longitudinal arm thereof, and the offset intermediate portion of the other frame being offset away from the first longitudinal arm thereof, hinge means pivotally connecting the second longitudinal arms of the frames at said offset intermediate portions between said outward end portions, spring means mounted on the second longitudinal arm of one of the frames and having a portion tensioned against the offset intermediate portion of the other frame and urging said frames toward each other so as to compress the first longitudinal arms of the frames together, and a hook member comprising a shank having a hook on one end and having another end, said another end being pivoted on the offset intermediate portion of the other of the frames offset away from the first longitudinal arm, said shank having a portion angulated with respect to the axis of the shank for engaging the offset intermediate portion of the other frame so as to lock the frames together with their first longitudinal arms in compressed relation.

2. In a garment hanger, two longitudinally elongated rectangular frames arranged in side by side relation, each frame comprising a first longitudinal arm, a second longitudinal arm, and end arms extending between longitudinally outward end portions of the longitudinal arms, the second longitudinal arms of the frames having laterally offset intermediate portions spaced from the longitudinally outward ends thereof and extending parallel to said first longitudinal arms of the frames, the offset intermediate portion of one frame being offset toward the first longitudinal arm thereof, and the offset intermediate portion of the other frame being offset away from the first longitudinal arm thereof, hinge means pivotally connecting the second longitudinal arms

of the frames at said offset intermediate portions between said outward end portions, spring means mounted on the second longitudinal arm of one of the frames and having a portion tensioned against the offset intermediate portion of the other frame and urging said frames toward each other so as to compress the first longitudinal arms of the frames together, and a hook member comprising a shank having a hook on one end and having another end, said another end being pivoted on the offset intermediate portion of the other of the frames offset away from the first longitudinal arm, said shank having a portion angulated with respect to the axis of the shank for engaging the offset intermediate portion of the other frame so as to lock the frames together with their first longitudinal arms in compressed relation, the said offset intermediate portions being disposed at acute angles with respect to the end arms of their frames.

3. In a garment hanger, two longitudinally elongated rectangular frames arranged in side by side relation, each frame comprising a first longitudinal arm, a second longitudinal arm laterally spaced from the first longitudinal arm, and end arms extending between longitudinally outward end portions of the longitudinal arms, the second longitudinal arms of the frames having laterally offset intermediate portions spaced from the longitudinally outward ends thereof and extending parallel to said first longitudinal arms of the frames, the offset intermediate portion of one frame being offset toward the first longitudinal arm thereof, and the offset intermediate portion of the other frame being offset away from the first longitudinal arm thereof, hinge means pivotally connecting the second longitudinal arms of the frames at said offset intermediate portions between said outward end portions, spring means mounted on the second longitudinal arm of one of the frames and having a portion tensioned against the offset intermediate portion of the other frame and urging said frames toward each other so as to compress the first longitudinal arms of the frames together, and a hook member comprising a shank having a hook on one end and having another end, said another end being pivoted on the offset intermediate portion of the other of the frames offset away from the first longitudinal arm, said shank having a portion angulated with respect to the axis of the shank for engaging the offset intermediate portion of the other frame so as to lock the frames together with their first longitudinal arms in compressed relation, the said spring means comprising a coil circumscribed on the second longitudinal arm of said one frame, said coil terminating at its opposite ends in portions bearing in opposite directions against the offset intermediate portion of one frame and an end arm of the other frame.
